OVERLOAD ATTACHMENT FOR SEMI-ELLIPTICAL SPRINGS

Herbert D. Boardman and Fritz Hansen,
Manchester, Iowa

Application April 8, 1949, Serial No. 86,328

2 Claims. (Cl. 267—29)

1

Our invention relates to overload attachments for semi-elliptical springs, and more particularly to such springs as are utilized in motor vehicles. As is well known, such semi-elliptical springs when subjected to long use and/or to overloads tend to flatten out, whereby to lose a considerable amount of their effectiveness.

With the foregoing in view, it is an object of our invention to provide an improved overload attachment for semi-elliptical springs.

A further object is to provide an improved overload attachment for semi-elliptical springs which includes an overload spring, means resiliently connecting opposite ends of the overload spring to opposite ends of the semi-elliptical spring, and rigid upwardly-extending extensions of said means resiliently loaded into supporting engagement with the semi-elliptical spring laterally inwardly of said opposite ends thereof.

Other objects and advantages reside in the particular structure of the invention, combination and arrangement of the several parts thereof, and will be readily understood by those skilled in the art upon reference to the attached drawing in connection with the following specification, wherein the invention is shown, described and claimed.

In the drawing:

Figure 1 is a fragmentary front elevation of a motor vehicle and a semi-elliptical spring therefor, showing the attachment according to the invention applied thereto;

Figure 2 is a horizontal sectional view taken substantially on the plane of the line 2—2 of Figure 1;

Figure 3 is a bottom plan view of the attachment in place on a semi-elliptical spring;

Figure 4 is a transverse vertical sectional view taken substantially on the plane of the line 4—4 of Figure 1, parts being omitted;

Figure 5 is a perspective view of an anchor member according to the invention apart from the rest of the structure.

Referring specifically to the drawing, wherein like reference characters have been used throughout the several views to designate like parts, 10 designates generally any suitable portion of the frame of a motor vehicle and 11 designates generally a semi-elliptical spring for the vehicle. The spring 11 is operatively connected to the frame 10 in any usual and/or well known manner, as by the center bolt 13 and U-bolts 14. The opposite ends 15 of the spring 11 are pivotally supported in the usual manner from spring shackles 16 connected to the axle 17 of the vehicle.

2

The device according to our invention includes a pair of hooks or anchor-providing means, generally indicated at 18, and best seen in Figure 5. In view of the fact that both of the anchors 18 are identical, it will suffice to describe but a single one of them. Thus, each anchor 18 includes a horizontally-disposed leg 19 and an upwardly-directed rigid arm 20 integral with the leg 19 to provide a substantially L-shaped anchor. Each anchor 18 has an upwardly-directed hook 21 formed integrally with the free end of the horizontal leg 19 thereof. As best seen in Figure 1, the hooks 21 are hooked over the opposite ends of the leaf spring 11 so as to dispose the horizontal legs 19 of the anchors 18 in oppositely-inwardly-directed relation below the leaf spring 11. The upstanding arms 20 of the anchors 18 have aligned holes 25, Figure 5, formed therethrough for the free passage of the shanks of a pair of inwardly-directed eye bolts 22. A contractile overload spring 23 is operatively connected to the eyes of the eye bolts 22 and is maintained in an adjusted tensioned condition by means of nuts 24 threaded on the shanks of the eye bolts 22 outwardly of the upwardly-directed arms 20 of the anchors 18.

As best seen in Figure 1, the lines A—A represent the horizontal plane of the pivotal axes of the pivotal connection of the hooks 21 with the opposite ends 15 of the leaf spring 11. Also, the line B—B of Figure 1 represents the horizontal plane through the bolts 22 and axis of the spring 23. It is noted that the plane of the line B—B is slightly below the plane of the line A—A, whereby the effect of the spring 23 is to load the upstanding arms 20 into supporting engagement with the under side of the leaf spring 11 between the opposite ends 15 thereof and the intermediate portion 12. In effect, the points 26 where the upper ends of the arms 20 engage the under side of the spring 11 comprise fulcrum-providing points about which the opposite ends 15 of the leaf spring are flexed under the load of the overload spring 23. Thus, not only does the overload spring 23 resist the flattening of the leaf spring 11 under a load by an inward pull on the opposite ends 15 thereof, but also resists such flattening by the upward thrust of the arms 20 on the under surface of the spring.

While we have shown and described what is now believed to be a preferred embodiment of the invention, it is to be understood that our invention is susceptible to other forms and expressions. Consequently, we do not limit ourselves to the precise structure shown and de-

scribed hereinabove except as hereinafter claimed.

We claim:

1. The combination with a vehicle having a pair of spaced spring shackles, a semi-elliptical leaf spring pivotally supported at its opposite ends by said shackles, said spring having an upwardly bowed intermediate portion supporting a load, of a pair of L-shaped anchors each positioned below said leaf spring and adjacent an end of the latter, the horizontal leg of each of said anchors being formed adjacent its free end with an upwardly directed hook, said hooks releasably and pivotally engaging the adjacent ends of said leaf springs, the vertical legs of the anchors being in confronting relation and being vertically arranged under the leaf spring, and resilient means secured to the vertical legs of said anchors below a line drawn between the pivotal engagement points of said hooks with the adjacent ends of said leaf spring, said means connecting said vertical legs together for normally urging the latter toward each other, the free ends of said vertical legs being in abutting engagement with the under side of said leaf spring centrally between said intermediate portion and the corresponding ends of the latter.

2. The combination with a vehicle having a pair of spaced spring shackles, a semi-elliptical leaf spring pivotally supported at its opposite

ends by said shackles, said spring having an upwardly bowed intermediate portion supporting a load, of a pair of L-shaped anchors each positioned below said leaf spring and adjacent an end of the latter, the horizontal leg of each of said anchors being formed adjacent its free end with an upwardly directed hook, said hooks releasably and pivotally engaging the adjacent ends of said leaf springs, and a coil spring operatively secured at its opposite ends to the vertical legs of said anchors below a line drawn between the pivotal engagement points of said hooks with the adjacent ends of said leaf spring, said coil spring connecting said vertical legs together for normally urging the latter toward each other, the free ends of said vertical legs being in abutting engagement with the under side of said leaf spring centrally between said intermediate portion and the corresponding opposite ends of the latter.
